BARBER'S AND BEAUTICIAN'S STERILIZING TRAY

Filed July 27, 1933

UNITED STATES PATENT OFFICE

1,973,156

BARBER'S AND BEAUTICIAN'S STERILIZING TRAY

Oreste R. Scioscia, Pittsburgh, Pa.

Application July 27, 1933, Serial No. 682,499

13 Claims. (Cl. 167—3)

This invention relates to improvements in sterilizers and particularly to those sterilizers adapted for the use in barber and beauty shops for the sterilization of tools and instruments.

5 In substantially all of the jurisdictions of the United States there are laws and ordinances regulating the sterilization of barbers' and beauty specialists' tools and instruments. It has been found that unless the facilities are placed adjacent to the operator's chair some barbers and beauty specialists will disregard the regulations. This disregard of the regulations has been observed more particularly during rush hours when it is most important that the regulations be observed.

10 15 In the construction of a sterilizer, care must be taken to make it effective, easily used and of a construction to receive all of the tools and instruments used by the operator.

The primary object of this invention is the provision of a sterilizer having a plurality of 20 different compartments, each suitable to the tools or implements to be sterilized.

Another object of the invention is a barber's or beauty shop sterilizer having a separate and 25 removable compartment for the clippers—particularly of the power or mechanical type.

Another and still further object of the invention is the provision of a sterilizer having a separate compartment for the clippers and having 30 two levels at which the clipper knives can be placed—above or below the level of the top of the sterilizer fluid.

Another and still further object of the invention is the provision of a barber's or beauty shop sterilizer having a clipper compartment with 35 supporting means to hold the clipper knives at either of the two levels and so constructed that the clipper handle may be in either a relative right, left or front position.

Another and still further object of the invention is the provision of a sterilizer having a plurality of compartments one of which is so formed as to receive a massage applicator below the surface of the sterilizer fluid and a hair brush above the applicator but with the lower ends of the brush bristles below the level of the sterilizer fluid.

Another and still further object of the invention is the provision of a sterilizer having a plurality of compartments including provision for holding an antiseptic solution and also means for making a small swab for applying the antiseptic solution to cuts or abrasions of the skin.

50 55 Other and further objects will be apparent to

those skilled in the art from a reading of the complete specification and claims.

Referring to the drawing wherein I have illustrated an embodiment of my invention.

Fig. 1 is a plan view of my invention.

Fig. 2 is a cross sectional view on the line 2—2 of Fig. 1.

Fig. 3 is a cross sectional view on the line 3—3 of Fig. 1.

Fig. 4 is a detached view of the removable sterilizer section containing the clipper compartment.

Fig. 5 is an end view of the sterilizer showing a part broken away for clearness.

Similar reference characters refer to the same or similar parts throughout the several views of the drawing.

In the drawing, 10 designates the main body of the sterilizer, 11 the brush sterilizing compartment having the lower sub-compartment 12 for receiving the massage applicators. At the sides of the sub-compartment 12 are the shoulders 13 upon which the brush rests during the sterilizing operation.

At the side of the brush compartment and in the side wall, is a cutaway section 14 for the handle of the brush to occupy when the cover, to be described, is in its closed position.

At the back of the brush compartment is another sterilizer compartment 15. This compartment 15 is deeper than the brush compartment 11 and is to sterilize such tools and instruments as shears, and other pointed instruments, tweezers, as well as razors. At the left side of the compartment are shown three sockets—the socket 16 for large or barbers' shears during the sterilizing operation, the socket 16^a to receive the small shears or manicure shears and the socket 17 to hold tweezers and other pointed instruments. These sockets 16 and 17 are connected to the main portion of the compartment by slots 16^b and 17.

At the opposite side of the compartment 15 are located two razor sockets 18 and 19. These sockets 18 and 19 are connected to the main portion of the compartment by slots 18^a and 19^a. The width of the slots 18^a and 19^a, and the proximity of the sockets 18 and 19 to the main portion of the compartment is such that the blades of the razors when in place, have their edges out in the main portion of the compartment 15. This construction protects the razor edge from injury and insures sterilization. At the tops of the sockets 18 and 19, are chamfered surfaces which I have designated 18^b, 19^b and 110

105

which act as guides to the razors when the latter are being inserted. At the bottoms of the slots 18, 19 are heel rests as at 19^a in Fig. 3, to support the heel of the razor.

5 Adjacent the compartment 15 are two dry sockets 21, 22 to receive the razors after sterilization and to hold them folded until needed for use. The sockets 18 and 19 are so placed as to permit the razor handles to fold down without 10 interference with each other.

At one side of the compartment 15 are two dry sockets 23, 24 to receive sterilized shears and retain them until needed for use. I also provide dry sockets 25, 26, 27 for holding tweezers or 15 other small sterilized articles until needed for use.

A very important feature of my sterilizer is the clipper sterilizing section. This section is shown as a box and is located in a socket adjacent the brush compartment and in the embodiment illustrated has a body portion 28 substantially square at the top and constructed of material which will not be stained or attacked by the sterilizing liquid, and may be for example of glass, stainless steel, hard rubber or bakelite.

On at least one side, and near but spaced from the bottom is a projecting portion which is shown as a ledge at 28^a. The compartment 30 within the clipper box 28 is or may be provided with any suitable sterilizing liquid. This sterilizing liquid is preferably placed so that its upper level is below the level of the projecting ledge 28^a.

35 The clippers (shown in dotted lines in its two positions) will be seen at 29^a, 29^b. With this construction, the clippers may be placed with the cutting knives at either one of the two levels—on the bottom for sterilization and after 40 sterilization on the ledge 28^a to drain and become dry.

One feature of this portion of my sterilizer is that provision is made to support the clippers at either of two levels and at the same time so 45 that the clippers may be taken from the sterilizer in a position with its gripping portion extending in one of a plurality of directions, to suit the convenience of the user. The form illustrated has provision to rest the clippers on the ledge 28^a 50 which is shown as extending only across one side and in such a structure, it is desirable to have the section constructed so that it may be placed in its socket or recess in any one of a plurality of positions. Accordingly, I have illustrated the 55 section 28 as being substantially square so that it may be placed so as to have the ledge 28^a at the rear or at either side, thus presenting the handle or gripping portion of the clippers at the right, left or in front at the option of the user.

60 Between the forward edge of the brush compartment 11 and the forward edge of the sterilizer and extending in front of the clipper box or compartment 28 is the comb tray 30. This tray 30 is long enough to receive the full length of a barber's comb and is provided throughout its length with corrugations which extend lengthwise. These corrugations receive the combs and retain them in the position in which the combs are placed, thus preventing a single comb from sliding down and lying flat on its side when alone in 70 the tray.

In order to provide for immediate treatment of cuts and abrasions with antiseptic solution, I have provided a compartment 31 for cotton, 75 a small compartment 32 for tooth picks or similar

long instruments and adjacent thereto, a compartment 33 for the solution. When the skin is scratched the operator takes a tooth pick from the compartment 32 and by placing one end in cotton and rolling the tooth pick between his fingers, some of the cotton is caused to adhere to the end of the pick to form a small swab. This is now dipped into the antiseptic solution and the cut or abrasion then treated. The tooth pick or other long instrument forms a convenient handle for the swab.

To prevent dust and dirt from entering the compartments when the sterilizer is not in use, I have provided covers, two for covering the rear or deep compartments and one for covering the brush and clipper compartments. Hinged to the rear edge as at 34 are the covers 35 having their forward edges extending to the forward edge of the compartment 15, one extending to cover the slots 16, 16', 17, 18 and 19 and the compartment 15 when not being used. The other cover, 35, covers the sockets 21, 22, 23, 24, 25, 26, 27 and the compartments 31, 32 and 33.

The forward or front cover 36 extends from end to end to cover the compartments 11 and 28 and is hinged at the forward edges at 37. When the sterilizer is not in use, the front cover 36 is swung forward and lies against the front face of the sterilizer.

The covers of the tray afford very convenient 105 surfaces on which may be placed advertisements of various articles. These advertisements may be placed on both the inside and outside of the covers so that they may be seen when the covers are open or closed. The advertisements may be 110 the same on both sides of the covers or they may be different so that a different advertising display will be made when the covers are open from that displayed when the covers are closed.

The legs 38 are provided to support the sterilizer.

Any suitable heating apparatus may be used if desired. One heating apparatus is illustrated in my co-pending application Serial Number 627,169 filed July 30, 1932, of which the invention disclosed in this application is an improvement.

While I have illustrated and described in detail an embodiment of my invention, it is to be understood that the disclosure is merely illustrative and that modifications and changes may 125 be made without departing from the spirit of my invention and within the scope of the appended claims.

Having described my invention what I claim and desire to secure by Letters Patent is:

1. A sterilizer for barbers' and beauty specialists' tools and instruments comprising a body portion having side walls providing a sterilizing compartment, supporting walls within the compartment to support the outer portions of the 130 bristles of a hair brush and a substantially circular space between the supporting walls to receive a massage applicator.

2. A sterilizer for barbers' and beauty specialists' tools and instruments comprising a hair brush compartment, a rest for a hair brush handle, a separate compartment for the clippers, and means at the side of the compartment to support the clipper knives at two different levels.

3. A sterilizer for barbers' and beauty specialists' tools and instruments comprising a hair brush compartment, a separate clipper compartment and means within the clipper compartment and extending from the side wall to support the 145 150

- clipper knives, at will above the bottom of the clipper compartments.
4. In a sterilizer for barbers' and beauty specialists' tools and instruments, a removable section having a clipper compartment, means for holding the section steady in any one of three positions to receive the clippers when the clipper handle is extended to the front, right or left and means within the compartment to, at will, support the clipper knives at either of two different levels.
5. In a sterilizer for barbers' and beauty specialists' tools and instruments, walls surrounding a compartment of a size and shape to receive clippers and means engageable at will without removal for supporting the clipper knives at either of a plurality of levels.
6. In a sterilizer for barbers' and beauty specialists' tools and instruments, walls surrounding a compartment of a size and shape to receive clippers and means forming a part of the walls for supporting the clipper knives with the clipper handle extending either to the right or left of the sterilizer and at a plurality of heights.
7. A sterilizer for barbers' and beauty specialists' tools and instruments comprising a hair brush compartment and a separate compartment for the clippers, the side wall having a projecting portion to, at will, support the clipper knives above the bottom of the compartment, the walls of the compartment being adjustable relative to the sterilizer as a whole so that the handle of the clipper may rest in a position toward the right, left, or front of the sterilizer.
8. A sterilizer for barbers' and beauty specialists' tools and instruments comprising a hair brush compartment and a separate compartment for the clippers, the walls of the clipper compartment being so constructed as to support the clippers in a position so that the handle may be to the right, left, or front relative to the sterilizer and having means to support the clipper knives at a plurality of levels.
9. A sterilizer for barbers' and beauty specialists' tools and instruments comprising a hair brush compartment and a separate compartment for the clippers, the walls of the compartment being adjustable relative to the sterilizer as a whole so that the handle of the clipper may rest in a position toward the right, left or front of the sterilizer.
10. In a sterilizer for barbers' and beauty specialists' tools and instruments, a removable section having a clipper compartment, and means for holding the section steady in any one of three positions to receive the clippers when the clipper handle is extended to the front, right or left.
11. In a sterilizer for barbers' and beauty specialists' tools and instruments, a removable section having a clipper compartment, means for holding the section steady in any one of three positions to receive the clippers when the clipper handle is extended to the front, right or left, and means within the compartment to, at will, hold the clipper knives above and off of the bottom of the compartment.
12. A sterilizer for barbers' and beauty specialists' tools and instruments comprising a body portion having side walls, a removable section having a clipper compartment, means for holding the section steady in any one of three positions to receive the clippers when the clipper handle is extended to the front, right or left, the section having means at the side and within the compartment to, at will, support the clipper knives at either of two different levels, a cotton compartment, a swab handle compartment and an antiseptic solution compartment for holding an antiseptic solution for the treatment of cuts and abrasions of the skin.
13. A sterilizer for barbers' and beauty specialists' tools and instruments comprising a body portion having side walls providing a sterilizing compartment, supporting walls within the compartment to support the outer portions of the bristles of a hair brush, a substantially circular space between the supporting walls to receive a massage applicator, a removable section having a clipper compartment, means for holding the section steady in any one of three positions to receive the clippers when the clipper handle is extended to the front, right or left, the section having means within the compartment to, at will, support the clipper knives at either of two different levels, a cotton compartment, a swab handle compartment and an antiseptic solution compartment for holding an antiseptic solution for the treatment of cuts and abrasions of the skin.
